UNITED STATES PATENT OFFICE.

ERNEST GODFREY SHAFFROTH, OF KALISPELL, MONTANA.

DRÉDGE-BUCKET.

1,202,594.

Specification of Letters Patent. Patented Oct. 24, 1916.

Application filed April 19, 1916. Serial No. 92,164.

To all whom it may concern:

Be it known that I, ERNEST G. SHAFFROTH, a citizen of the United States, and a resident of Kalispell, in the county of Flathead and State of Montana, have invented a new and Improved Dredge-Bucket, of which the following is a full, clear, and exact description.

My invention has for its object to provide 10 a dredge bucket which may be operated by a single line, and which automatically opens and closes at the proper time; the construction is such that there is no danger of the bucket opening until it reaches a predetermined height, and there is no danger of the 15 bucket closing except at the place desired.

Additional objects of the invention will appear in the following specification in which the preferred form of the invention 20 is described.

In the drawings similar reference characters denote similar parts in all the views, in which—

Figure 1 is a side elevation of my invention showing the hoop in section; Fig. 2 is 25 a view similar to that shown in Fig. 1, but with the parts in the position which they assume when the bucket jaws are opened before the bucket is lowered; Fig. 3 is a view similar 30 to those shown in Figs. 1 and 2, but with the bucket jaws at the ground and the parts in position to close the bucket jaws as the bucket is raised; Fig. 4 is a sectional view on the line 4—4 of Fig. 1; Fig. 5 is an enlarged 35 sectional view on the line 5—5 of Fig. 6; and Fig. 6 is an enlarged sectional view on the line 6—6 of Fig. 5.

The bucket is constructed with a vertical frame, two sleeves being slidably mounted 40 on this frame, arms on the bucket jaws being pivotally connected at their inner ends to one of the sleeves, and at their outer ends to the other sleeve, so that the bucket jaws may be operated by sliding one sleeve on the frame relatively to the other. When 45 the bucket is lowered, the sleeves will be disposed one above the other, and be supported by a stop on the frame, which holds the bucket jaws open; but when the bucket jaws 50 come in contact with the bottom their downward movement will be interrupted, although the vertical frame will continue to descend relatively to the bucket jaws and

sleeves until another stop on the vertical frame comes in contact with the upper 55 sleeve, when pivoted catches on the frame will engage this upper sleeve, so that when the vertical frame is raised relatively to the lower sleeve, the upper sleeve will be moved away from the lower sleeve to close the 60 bucket jaws. The bucket jaws are opened by the movement of the upper portion of the frame into a hoop which engages the catches to operate the latter and free the upper sleeve, thus permitting the downward 65 movement of the upper sleeve relatively to the frame and the lower sleeve, to open the bucket jaws. As a means for holding the bucket jaws down when the upper sleeve is moved upwardly by the catches on the 70 frame and relatively to the lower sleeve, I provide the vertical frame with bearings in which a shaft is journaled, drums being secured to this shaft on one of which the lifting line is wound in one direction, cords being secured to the lower sleeve and being wound around the other drums in the opposite direction, so that when the lifting 75 line is drawn tight at the commencement of the upward movement, it will rotate the 80 shaft to wind up the cords, thereby holding the lower sleeve down until it is engaged by the lower stop on the vertical frame.

Having briefly described the construction and operation of the invention, I will now 85 describe in greater detail the construction, and will point out in the specification, the different elements referred to.

By referring to the drawings, it will be seen that a vertical frame is provided having 90 two members 10 spaced apart. Slidably mounted on the frame members 10 there is a sleeve 11 having depending arms 12 connected at their lower ends by a head 13 to which are pivoted the inner ends 14 of arms 95 15 which extend from bucket jaws 16. Slidably mounted on the depending arms 12 of the sleeve 11 there is a second sleeve 17 which is connected with the outer ends 18 of the bucket jaw arms 15, by links 19. The 100 links 19 are of such a length that when the sleeve 17 is supported by stops 20 and the sleeve 11 rests on the sleeve 17, the bucket jaws 16 will be in open position, as illustrated in Fig. 2 of the drawings, but when 105 the sleeve 11 is raised relatively to the sleeve

17, it will serve to close the bucket jaws 16, as illustrated in Fig. 1 of the drawings.

The stops 20 are integral with a spacing member 21 which is disposed between the 5 frame members 10. Below the spacing member 21 there are bearings 22 in the frame members 10 in which a shaft 23 is journaled, this shaft 23 being also journaled in bearing members 24 which are slidably 10 disposed in guideways 25 in the depending arms 12 of the sleeve 11. Disposed between the frame members 10 there is a drum 26 which is secured to the shaft 23, there being additional drums 27 which are secured to 15 the shaft 23 at the outer sides of the bearing members 24. A lifting line 28 is disposed down between rollers 29 at the upper portion of the frame members 10, this lifting line extending through an opening 30 in 20 one of the stops 20, and being wound around the drum 26 in one direction, and being secured thereto, there being cords 31 which are secured to the sleeve 17 and which are wound around the drums 27 in the opposite 25 direction. This is done so that when the lifting line 28 starts to lift the vertical frame, it will rotate the drum 26, by means of which the drums 27 will be rotated to draw down on the cords 31 and thereby 30 hold the sleeve 17 substantially stationary while the frame and the sleeve 11 are raised relatively thereto. This means is provided so that the bucket jaws 16 will close in such a manner as to obtain the best results. By 35 referring to Fig. 4 of the drawings, it will be seen that the depending arms 12 of the sleeve 11 have guideways 32 in which the frame members 10 are disposed.

When the bucket is lowered, the parts will 40 be in the position illustrated in Fig. 2, that is, the sleeve 17 will rest on the stops 20 and the sleeve 11 will rest on the sleeve 17, the bucket jaws 16 being open when the sleeves 11 and 17 are in the said position relatively 45 to the frame members 10, which position they will retain until the bucket jaws 16 reach the ground, as illustrated in Fig. 3 of the drawings, when the further downward movement of the bucket jaws will be 50 interrupted, while the weight of the frame members 10 will permit the frame to descend relatively to the sleeves 11 and 17 to the position illustrated. The frame members descend relatively to the sleeves 11 and 55 17 until the upper sleeve 11 is disposed at or in close proximity to stops 33 on the frame members 10, catches 34 being then in position to engage members 11^a of the sleeve 11. These catches 34 are pivoted to the 60 frame members 10 at 35, there being pins 36 in the frame members 10 which move in cut-away portions 37 in the catches 34 to limit the movement of the said catches, these catches 34 being so weighted that they 65 will operatively engage the members 11^a on

the sleeve 11 when the sleeve 11 reaches a position adjacent the stops 33 on the frame members 10. The sleeve 11 will by this means be temporarily secured against movement relatively to the frame members 10, so 70 that when the lifting line 28 is raised to lift the bucket, the sleeve 11 will move upwardly with the frame members 10 and the sleeve 17 will be held substantially in a stationary 75 position during the first part of this upward movement because of the winding of the cords 31 on the drum 27, which will be brought about by the unwinding of the lifting line 28 from the drum 26 in the manner which has been described. However, until 80 the frame members 10 have moved up sufficiently far to carry the sleeve 11 a sufficient distance from the sleeve 17 to close the bucket jaws 16, the stops 20 will engage the sleeve 17 to carry upwardly the said 85 sleeve 17, with the frame members 10, as illustrated in Fig. 1 of the drawings. The lifting line 28 passes through a hoop 38 connected with a frame 39 in which a sheave 40 is journaled, the lifting line 28 passing 90 over this sheave 40 in a manner well understood. When the upper portion of the frame members 10 pass into the hoop 38, the hoop 38 will engage the upper portions 34^a of the catches 34 to operate the catches, 95 thereby freeing the sleeve 11 therefrom, it being understood that the boom 41 will first be moved to a position over which the contents of the bucket are to be deposited. When the upper portions 34^a of the catches 100 34 move into engagement with the hoop 38, they will free the sleeve 11, so that the said sleeve 11 will fall to the position illustrated in Fig. 2, thereby opening the bucket 105 jaws 16.

Having thus described my invention, I claim as new and desire to secure by Letters Patent:

1. In a device of the class described, a frame, a member movably mounted on the frame and having depending arms, a second member movably mounted on the frame between the top of the body of the first member and the bottom of the depending arms, bucket jaws, pivotal means connecting the bucket jaws with the arms of the first member, additional pivotal means at the bucket jaws connecting the bucket jaws with the second member, and a catch adjacent the top of the frame for supporting the first member, the catch having an operating portion positioned to be struck by an overhead member as the bucket is raised to operate the catch, thereby freeing the first member.

2. In a device of the class described, a vertical frame, two sleeves slidable on the frame, a stop on the frame below the sleeves, bucket jaws, pivotal means connecting the outer portions of the bucket jaws with one

- of the sleeves, additional pivotal means connecting the bucket jaws with the other sleeve, and a catch for holding the last sleeve spaced above the other sleeve.
5. 3. In a device of the class described, a vertical frame, two sleeves slidable on the frame, a stop on the frame below the sleeves, bucket jaws, pivotal means connecting the outer portions of the bucket jaws with one of the sleeves, additional pivotal means connecting the bucket jaws with the other sleeve, a catch on the frame for engaging one of the sleeves to hold the latter spaced from the other sleeve, and means for engagement by the catch for operating the latter as the frame is raised to permit the sleeve held by the catch to fall and thereby open the bucket jaws.
4. In a device of the class described, a vertical frame, two sleeves slidable on the frame, a stop on the frame below the sleeves, bucket jaws, pivotal means connecting the outer portions of the bucket jaws with one of the sleeves, additional pivotal means connecting the bucket jaws with the other sleeve, a catch on the frame for holding one of the sleeves spaced from the other sleeve, a hoop, and a line secured to the frame and extending through the hoop for bringing the catch into engagement with the hoop, thereby operating the catch to free the sleeve held thereby when the frame is raised by the line.
5. In a device of the class described, a vertical frame, two sleeves slidable on the frame relatively to each other, a stop on the frame below the sleeves, bucket jaws, pivotal means connecting the bucket jaws with one of the sleeves, pivotal means spaced from the first pivotal means at the bucket jaws and connecting the bucket jaws with the other sleeve, bearings in the frame, a shaft journaled in the bearings, two drums secured to the shaft, a supporting line wound in one direction around one of the drums, a cord wound in the other direction around the other drum and secured to a sleeve, and means for holding the other sleeve spaced from the last mentioned sleeve.
50. 6. In a device of the class described, a vertical frame, two sleeves slidable on the frame and relatively to each other, a stop on the frame below the sleeves, bucket jaws, pivotal means connecting the bucket jaws with one of the sleeves, additional pivotal means spaced from the first pivotal means at the bucket jaws connecting the bucket jaws with the other sleeve, a catch on the frame for engaging one sleeve to hold the latter spaced from the other sleeve, and means for engagement by the catch to open the latter and free the sleeve supported by the catch.
7. In an article of the class described, a vertical frame, a sleeve slidable on the

frame and having depending arms, bucket jaws having inwardly extending arms pivoted to the depending arms, a second sleeve slidable upon the depending arms, links connecting the second sleeve with the bucket jaw arms, a stop on the frame below the second sleeve, and means for holding the first sleeve spaced above the second sleeve.

8. In an article of the class described, a vertical frame, a sleeve slidable on the frame and having depending arms, bucket jaws having inwardly extending arms pivoted to the depending arms, a second sleeve slidable on the depending arms, links connecting the second sleeve with the bucket jaw arms, a stop on the frame below the second mentioned sleeve, a lifting line secured to the frame, a hoop through which the lifting line extends, and a catch on the frame adapted to be operated by engagement with the hoop for holding the first mentioned sleeve spaced above the second mentioned sleeve.

9. In an article of the class described, a vertical frame having bearings, a sleeve slidable on the frame and having depending arms, bucket jaws having inwardly extending arms pivoted to the depending arms, a second sleeve slidable on the depending arms, links connecting the second sleeve with the bucket jaw arms, a stop on the frame below the second sleeve, means for holding the first sleeve spaced above the second sleeve, a shaft journaled in the bearings, two drums, a lifting line disposed around one of the drums in one direction and secured to the said frame, and a cord secured to the second sleeve and disposed around the other drum in the other direction.

10. In an article of the class described, a vertical frame having bearings, a sleeve slidable on the frame and having depending arms, bucket jaws having inwardly extending arms pivoted to the depending arms, a second sleeve slidable on the depending arms, links connecting the second sleeve with the bucket jaw arms, a stop on the frame below the second sleeve, a shaft journaled in the bearings, two drums, a lifting line disposed around one of the drums in one direction and secured to the said frame, a cord secured to the second sleeve and disposed around the other drum in the other direction, a hoop through which the lifting line extends, and a catch on the frame adapted to be operated by engagement with the hoop, the catch normally holding the first sleeve spaced above the second sleeve.

11. In an article of the class described, a frame, a member movably mounted on the frame and having depending arms, a second member movably mounted on the frame between the top of the body of the first mem-

- ber and the bottom of its said arms, the second member being adapted to limit the downward movement of the first member, bucket jaws, pivotal means connecting the bucket jaws with one of the members, additional pivotal means spaced from the first pivotal means at the bucket jaws, connecting the bucket jaws with the other member, a stop on the frame for limiting the downward movement of the second member, and a catch adjacent the top of the frame for supporting the first member, the catch being positioned to be struck by an overhead member as the bucket is raised for the purpose specified.
12. In an article of the class described, a frame having two vertically extending members spaced apart, a transverse shaft journaled in bearings in the frame members, a drum disposed between the frame members and secured to the shaft, additional drums secured to the shaft at the outer sides of the frame members, transverse members spaced apart and connecting the upper portions of the frame members, a lifting line extending down between the transverse members and wound in one direction around the first drum, a sleeve slidable on the frame members, cords secured to the sleeve and wound in the other direction around the additional drums, bucket jaws, an additional sleeve slidable on the frame members, means connecting the bucket jaws with the first sleeve, means spaced from the first sleeve at the bucket jaws connecting the bucket jaws with the second sleeve, and means on the frame for holding the second sleeve spaced above the first sleeve.
13. In an article of the class described, a frame having two vertically extending members spaced apart, a transverse shaft journaled in bearings in the frame members, a drum disposed between the frame members and secured to the shaft, additional drums secured to the shaft at the outer sides of the frame members, transverse members spaced apart and connecting the upper portions of the frame members, a lifting line extending down between the transverse members and wound in one direction around the first drum, a sleeve slidable on the frame members, cords secured to the sleeve and wound in the other direction around the additional drums, bucket jaws, an additional sleeve disposed above the first sleeve and having depending arms extending down within the first sleeve, means connecting the bucket jaws with the first sleeve, means spaced from the first sleeve at the bucket jaws connecting the bucket jaws with the second sleeve, and means on the frame for holding the second sleeve spaced above the first sleeve.
14. In a device of the class described, a frame having two vertically extending members spaced apart, a transverse shaft journaled in bearings in the frame members, a drum disposed between the frame members and secured to the shaft, additional drums secured to the shaft at the outer sides of the frame members, transverse members spaced apart and connecting the upper portions of the frame members, a lifting line extending down between the transverse members and wound in one direction around the first drum, a sleeve slidable on the frame members, cords secured to the sleeve and wound in the other direction around the additional drums, bucket jaws, an additional sleeve disposed above the first sleeve and having depending arms extending down within the first sleeve, means connecting the bucket jaws with the first sleeve, means spaced from the first sleeve at the bucket jaws connecting the bucket jaws with the second sleeve, and means on the frame for holding the second sleeve spaced above the first sleeve.
15. In an article of the class described, a frame, a member movably mounted on the frame and having depending arms, a second member movably mounted on the frame between the top of the body of the first member and the bottom of its said arms, the second member being adapted to limit the downward movement of the first member, bucket jaws, pivotal means connecting the bucket jaws with one of the members, additional pivotal means spaced from the first pivotal means at the bucket jaws, connecting the bucket jaws with the other member, a stop on the frame for limiting the downward movement of the second member, a catch adjacent the top of the frame for supporting the first member, the catch being positioned to be struck by an overhead member as the bucket is raised for the purpose specified, a lifting line connected with the frame, and means in connection with the lifting line for drawing down the second member against the stop.
16. In a device of the class described, a vertical frame, hoisting means secured to the frame, a sleeve slidable on the frame and having depending arms, bucket jaws having inwardly extending arms pivoted to the depending arms, a second sleeve slidable on the depending arms, links connecting the second sleeve with the bucket jaw arms, a stop on the frame below the sleeves, means for holding the first sleeve spaced above the second sleeve, and means disposed above the frame for engagement by the first means as the frame is raised to free the first means.
17. In a device of the class described, a vertical frame, a sleeve slidable on the frame and having depending arms, bucket jaws having inwardly extending arms free from the frame.

the frame and pivoted to the depending arms, a second sleeve slidable on the frame and relatively to the first sleeve, links connecting the second sleeve with the bucket 5 jaw arms, a stop on the frame below the second sleeve, and means for holding one sleeve spaced above the other sleeve.

In testimony whereof I have signed my name to this specification in the presence of two subscribing witnesses.
